COMPOSITE LOOM

Anselm De Ghetto, Clifton, N. J., assignor to National Rubber Machinery Company, Akron, Ohio, a corporation of Ohio

Application August 26, 1942, Serial No. 456,170

4 Claims. (Cl. 139—13)

This invention relates to looms such as may be used for the weaving of continuous tubing as for hose or the like.

One purpose of the invention is to provide a composite loom structure for weaving tubing on a fixed spindle or onto a pole or mandrel which may be fed through the loom in synchronism with its weaving mechanism, the apparatus being readily convertible from one use to the other.

Another purpose of the invention is to provide in a loom structure means for conveying the warp threads through the structure at a determinate speed and a tensioning means for the warp thread driven in synchronism with the thread conveying means to eliminate breakage of the warp threads.

Another purpose of the invention is to provide heddles so constructed as to carry the warp threads clear of the shuttle in leading them to the spindle or to the pole or mandrel to which they are applied.

The foregoing and other purposes of the invention are obtained in the loom structure illustrated in the accompanying drawings and described below. It is to be understood that the invention is not limited to the specific form thereof shown and described.

Of the accompanying drawings:

Figure 1 is a perspective view of a loom embodying the invention, looking at the apparatus from an angle toward the feed end of the machine when used for weaving on a fixed spindle.

Figure 2 is a perspective view of the apparatus looking at it from an angle toward the delivery end of the machine when weaving on a pole or mandrel.

Figure 3 is a vertical section through the weaving unit.

Figure 4 is an elevation of the feeding unit at the delivery end thereof.

Figure 5 is an end elevation of the tube-conveying mechanism at the delivery end of the loom when tube is being woven on a fixed spindle.

Figure 6 is a similar view at the delivery end of the loom showing the device when adapted for weaving on a pole or mandrel.

Referring to the drawings, the numeral 10 indicates a suitable frame structure which may have at the feed end of the apparatus a pair of uprights 10a, 10a, the frame structure being such that the loom may be mounted as shown in Figures 1 and 2 for operation as a horizontal loom, or may be tilted so that the portion of the frame extended to form uprights 10a may constitute the base of a vertical loom.

The loom structure comprises a weaving unit indicated generally by the numeral 11 and which may be of the general structure and design of the weaving unit 10 shown in the loom apparatus disclosed in a co-pending application of the present inventor, Serial No. 350,230, filed August 3, 1940. It will be sufficient, it is believed, for the present application to limit its description of the weaving unit 11 to features thereof which are not shown and described in the co-pending application referred to.

For supplying the warp thread to the unit 11 a rack structure may be arranged under frame 10 as indicated generally at 12 on which may be mounted creels 13, 13 of warp thread which may be guided therefrom by suitable means well known in the art as illustrated in the drawings whereby the warp threads are extended to tension roll 14 of a known type and about which 20 the warp threads may be wound and extended therefrom to the weaving unit 11 in the known manner as illustrated.

Tension roll 14 may have the usual adjustable brake 14a associated therewith for determining 25 the tension to be maintained on the warp threads.

In the loom structure in the above referred to co-pending application the warp threads are guided to the pole or mandrel on which the tube or hose is being formed in such a way as to bear 30 upon the shuttle. In accordance with the present construction the thread is extended to elongated guiding tubes 15, 15 associated with the usual cam operated sliders or heddles 16, so that the thread is carried clear of the shuttle indicated at 17, the thread extending from the tube 35 to the spindle 18 (see Figure 3) to be interwoven with thread supplied by the shuttle which is guided onto the spindle 18 (Figure 3) or mandrel M (Figure 2) by spreaders 19, 19 which correspond in general to the spreaders indicated at 40 15c in the co-pending application referred to. The spindle 18 may be removably mounted at the delivery end of the weaving unit 11 in the bore 11a as by bushing 18a.

45 The sliders or heddles 16 may be operated by the cam mechanism shown in Figure 3 which corresponds in every substantial respect to that operating the sliders or heddles in the loom unit shown in the co-pending application referred to.

50 To adapt the loom structure for conversion to use on poles or mandrels on which the tube or hose may be woven, there is arranged at the feed end of the machine a pair of feed rollers 20, 20, the upper one of which may be mounted on the bracket 21 hinged at 22 on a bracket 23 which

supports the lower feed roller 20, pressure of the upper roll 20 upon the lower roller 20 being determined by weights 24 on the hinged arm 21. Rollers 20 may be geared to each other and may be driven by suitable chain and sprocket mechanism housed at 25 which may be driven by a cross shaft housed at 26 from a shaft 27 extending along the top of frame 10, and mounted in suitable bearings at 28, 28, the suitable gearing between shaft 27 and the cross shaft being housed at 29.

In order to drive the tension roll 14 in synchronism with the speed of the warp threads as determined by the speed of the feeding drum to be described, it may be mounted on the shaft 30 mounted in bearings such as indicated at 31 and having thereon a pulley 32 driven by a belt 33 from a pulley (not shown) on the cross shaft which is housed at 26.

The drive motor for the unit 11 may drive the unit through suitable change-speed gearing (not shown) and described in the aforesaid co-pending application and through the pulley arrangement or otherwise, housed at 34, the drive motor being indicated at 35. Shaft 27 is arranged to be driven in synchronism with the weaving unit 11 from motor 35 through the change-speed gearing and shaft 36 and gearing 37.

At the delivery end of the machine there is a feeding drum 38 about which the tubing may be wound as it issues from the weaving apparatus 11, the feeding drum 38 being driven from shaft 27 through suitable gearing housed at 29a and 29b (see Figure 2) and as best illustrated at Figure 5. Shaft 27 may have a gear 39 thereon meshed with a gear 40 for driving a sprocket at 41 over which is trained a sprocket chain 42 driving a sprocket 43 on shaft of drum 38 which may be mounted on bracket 44. Gearings 39 and 40 may also drive the sprocket 45 through suitable chain and sprocket mechanism not shown but housed at 29b to drive a feed roller 46. Associated with the feed roller 46 is the co-operating feed roller 47 mounted on a bracket 48 which is hinged at 49 and has weights 48a, 48a thereon for applying determinate pressure of roller 47 on woven tubing indicated at T passing between the feed rollers 46 and 47. Associated with the feeding drum 38 is a deflector 50 for causing windings on the feeding drum 38 to be deflected onto a tapered portion 38a on the periphery of feeding drum 38 from whence the tubing may be trained to pass between the rollers 46 and 47. The deflector 50 may be mounted on an arm 51 hinged at 52 which may be weighted as indicated at 53 to control the pressure of deflector 50 on the periphery of feeding drum 38.

When it is desired to convert the apparatus to weaving a tube upon a pole or mandrel indicated at M in Figures 2 and 6, the arm 51 carrying deflector 50 may be removed from the hinge mounting at 52 and may be replaced by arm 49 carrying pressure roll 47 which may be removed from its hinge mounting at 49 and mounted on the hinge at 52. Thus a pole or mandrel M may be supported to be fed through the loom by passing between the feed rollers 20 at the feed-end of the machine and between the feeding drum 38 and the feed roller 47 at the delivery end of the machine as shown in Figures 2 and 6.

In the operation of the loom for weaving on the fixed spindle 18 as indicated in Figures 1, 3, 5, the warp threads 13 are fed up over the tension roll 14 which is driven by belt 32 at a slightly higher speed than the feeding drum 38 and the feed rolls

46 and 47 and which has tension applied by the brake 14a so that the warp threads may be passed through the loom by the substantially synchronized speed of the tension roll 14 with the feeding drum 38 and feed rollers 46 and 47, thus preventing breakage of the warp threads. As the woven tube passes from the delivery unit 11, it passes to the feeding drum 38 and around the feeding drum several times and finally to the feed rollers 46 and 47 from between which it issues from the loom. Due to the hinge action of the deflector arm 51 and of the arm 48 any knots or imperfections or/and variations in the thickness of the tube will merely cause hinging action of the arms, such knots or irregularities not preventing free passage of the tubing from the machine.

When it is desired to convert the machine from weaving on the fixed spindle 18 to weaving on a mandrel such as M, the bushing 18a with spindle 18 is removed and the mandrel will be fed through the loom as indicated in Figures 2 and 6, being passed between the feed rollers 20 through bore 11a of unit 11 and between the feeding drum 38 and feed roller 47 which propel the mandrel through the loom in synchronism with the weaving unit 11. In making a conversion of the apparatus to use for weaving on mandrel M, it is merely necessary to remove the hinge bracket 51 (see Figure 5) and replace it by the hinge bracket 48, the roller 47 thereon, in cooperation with the feeding drum 38 being aligned with the feed rollers 20. The pick of the woof thread applied to the mandrel M, of course, will be determined by the speed at which the mandrel M is fed through the apparatus.

In all uses of the apparatus, the guiding tubes 15 on the slider or heddle 16, which carry the warp threads, guide the warp threads either to the spindle 18, as indicated in Figure 3, or to the pole or mandrel M in such a way as to clear the shuttle 17.

Modifications of the invention obviously may be resorted to without departing from the spirit thereof or the scope of the appended claims.

What is claimed is:

1. A loom structure having in combination means for feeding woven tubing from the delivery end thereof, a weaving unit for the production of such tube, means for supplying warp threads to said weaving unit, a tension roller about which said warp threads are applied to said weaving unit, and means for driving said tension roller and said feeding means in substantial synchronism relatively of each other, said driving means including a slip driving connection to said tension roller.

2. A loom structure having in combination means for feeding woven tubing from the delivery end thereof, a weaving unit for the production of such tube, means for supplying warp threads to said weaving unit, a tension roller about which said warp threads are applied to said weaving unit, and means for driving said tension roller and said feeding means at predetermined speeds in substantial synchronism with each other, said tension roller driving means including a slip driving connection and being adapted to drive said roller at slightly higher speed than that of the tubing-feeding means, said tension roller having a brake thereon operable through said slip driving connection to restrict the speed of said roller and thereby to maintain desired tension in said warp threads.

3. A loom structure for weaving tubing and including a weaving unit having a bore and having

removably mounted in said bore a fixed spindle, said bore being arranged for a passage therethrough of a moving pole or mandrel toward a delivery end of said unit when said spindle is removed from said unit, means for weaving tubing continuously either on said fixed spindle or said moving mandrel, and means for supporting and driving a mandrel through said unit including means at the delivery end thereof convertible to use either for receiving tubing woven on the fixed spindle and feeding the tubing from the loom or for supporting and propelling the mandrel through the loom.

4. A loom structure for weaving tubing and including a weaving unit having a bore adapted to have removably mounted therein a fixed spindle and arranged for a passage therethrough of a moving pole or mandrel when said spindle is re-

moved from said unit, means for weaving tubing continuously either on said fixed spindle or said moving mandrel, means at the feed end of the said unit for supporting and driving a mandrel through the unit and means at the delivery end of the machine convertible to use either for receiving tubing woven on the fixed spindle and feeding it from the loom or for supporting and propelling a mandrel through the loom, said last named means including a feeding drum and a pair of feed rollers associated therewith, a deflector associated with the feeding drum, one of said feed rollers being adapted to be interchangeably mounted with said deflector in association with said feeding drum for propelling the mandrel.

ANSELM DE GHETTO.
